CLAIM

The ornamental design for spectacles as shown and described.

DESCRIPTION

FIG. 1 is a top front perspective view of spectacles according my design;

FIG. 2 is a rear elevational view thereof;

FIG. 3 is a front elevational view thereof;

FIG. 4 is a right-side elevational view thereof, the left side being a mirror image thereof;

FIG. 5 is a top plan view thereof;

FIG. 6 is a bottom view thereof; and,

FIG. 7 is an enlarged top view of the hinge area.

The broken lines in the drawings are shown for the purpose of illustrating portions of the spectacles that form no part of the claimed design.

1 Claim, 7 Drawing Sheets
